UNITED STATES PATENT OFFICE

2,328,366

TABLE TENNIS BAT

Elmer J. Timmermann, Glendale, Calif.

Application July 28, 1942, Serial No. 452,596

3 Claims. (Cl. 273—76)

This invention relates to a table tennis bat. Objects of the invention are to provide an improved table tennis bat composed of a unitary body including a blade and a handle integrally united with the blade and composed of the same material and constructed so that the entire device is of light weight and the blade is comparatively resilient; to provide a table tennis bat having a unitary body and handle composed of aluminum or other light weight metal, or composed of solidified plastic material, the blade being provided with an integral marginal flange or frame on each of the two opposite sides thereof merging evenly with the handle; and to provide a hollow handle integrally united with the blade by a connecting portion merging smoothly and symmetrically with the blade and the marginal flanges formed on opposite sides of the body.

Another object of the invention is to provide an improved table tennis bat having a unitary metallic or non-metallic body portion, and a homogeneous handle integrally united with said body portion, said body portion including a resilient blade having numerous perforations to obtain relatively light weight and to increase the resiliency and flexibility of the blade; in combination with a section of relatively inelastic textile material adhesively attached to each side of the blade and extending across and closing said perforations, and a sheet of rubber or similar elastic material attached to the outer surface of each of said sections by vulcanization, or other attaching means, and thereby held extended and spread uniformly and smoothly upon the blade.

Other objects and advantages of the invention should be apparent from the following description, reference being made to the annexed drawing, in which—

Fig. 1 is a side elevation of my improved table tennis bat, portions of the rubber sheet and the attached textile section being removed.

Fig. 2 is a side edge elevation of my improved table tennis bat.

Fig. 3 is a cross-sectional view of the handle approximately on the line 3—3 of Fig. 1.

Fig. 4 is an enlarged sectional view on the line 4—4 of Fig. 1, showing perforations in the blade and also showing the relationship of the textile sections attached directly to opposite sides of the blade and the elastic facings attached to outer sides of said textile sections.

Fig. 5 is a similar sectional view showing a blade without the perforations and having textile sheets attached directly to opposite sides of the blade throughout their adjacent areas, and

elastic facings attached to the outer sides of said textile sections.

The body of the device as shown may be composed of an appropriate metallic substance such as cast silica aluminum, or may be composed of solidified plastic material having the essential quality of resiliency.

As shown in Figs. 1 and 4, the blade 1 has numerous holes 2 which substantially reduce the weight of the bat below that of a solid bat of the same dimensions and which also increase resiliency. The bat is substantially oval in side elevation. The blade is formed with an integral homogeneous enclosing frame composed of two laterally extended flanges 3, thus providing a frame wholly surrounding the blade and having its outer surface rounded, as clearly shown. A handle extends from integral connection with one end of the blade and is integrally united with the blade by a connecting portion 4 approximately the same thickness in side elevation as the thickness of the blade including the flanges 3.

The handle is hollow and comprises two approximately flat walls 5 having spots or knurls 6 on their outer surfaces and integrally connected along their margins by smooth rounded portions 7. Openings 8 are formed in each of the rounded connecting portions 7, and an opening 9 is formed at the outer end of the handle. These openings permit free circulation of air into and through the handle, tending to diminish perspiration during warm weather. The openings 8 cooperate with the spots or knurls 6 to afford a better grip and prevent the handle from turning in the hand of the player. The handle is substantially oval in cross-section (Fig. 3).

A substantially inelastic section 10 is cemented or otherwise adhesively attached to each side of the blade. The inelastic sections 10 are of the same area as the area of the blade bordered by the flange 3, so that each side of the blade is completely covered by the attached section 10. The edge of the section 10 on each side of the blade fits closely against and is cemented to the inner surface of the flange 3. A sheet 11 of rubber or similar elastic material is attached to the outer surface of each section 10 by vulcanization, cement, or other attachment means, and thereby held securely in connection with the bat 50 so that the edges of said sheets 11 abut closely against the inner surfaces of the flanges 3. The edges of the sheets 11 may be cemented to the flanges 3. Numerous projections 12 are formed integral with the outer surface of each sheet 11 and project beyond the planes of the flanges 3.

(Fig. 4). The surfaces of the sheets 11 are in the same planes as the outer surfaces of the flanges 3. In this construction, the perforations 2 constitute cells that are filled with air, increasing the resiliency of the composite facings including the textile sections 10 and the rubber sheets 11.

The construction shown in Fig. 5 is the same as that already described, with the exception that the openings 2, functioning as air cells, are omitted, and the textile sections 10 are cemented throughout the length and width thereof directly to the surfaces of the blade 1. This modified construction in which the openings or air cells 2 are omitted contemplates an increase in the resiliency of the material of which the blade is formed. Thus, when the material is highly resiliency, the openings or air cells 2 may be omitted; and, when the coefficient of resiliency of the metal is below that desired for the blade, the resiliency may be increased by forming the holes or air cells 2.

From the foregoing, it is apparent that this invention, comprising a unitary resilient body portion, is substantially infrangible and will not become permanently bent or warped, or otherwise distorted under changing conditions of temperature and humidity. The device is easily handled in playing the game of table tennis because it is of light weight, the formation of the handle affords a strong retaining grip to prevent the handle from turning in the hand of the player, and it is practically impossible for the rubber sheet to become detached or curled from the blade.

I claim:

1. In a table tennis bat, a body comprising a relatively thin resilient blade having numerous holes of relatively large diameter therethrough, flanges integral with and projecting laterally beyond the margins of said blade and leaving said blade substantially resilient, and a handle integral with and projecting longitudinally beyond said flanges and said blade at one end of the latter; a substantially inelastic textile section adhesively attached to each side of said blade and extending across and covering the ends of said holes and having its edge adjacent to the inner side of the adjacent one of said flanges; and a sheet of elastic material attached to and wholly covering the outer side of each of said sections and having its edge engaging the inner side of said adjacent flange and having its outer surface approximately in the same plane with the outer surface of said adjacent flange.

2. In a table tennis bat, a body comprising a relatively thin resilient blade, flanges integral with and projecting laterally beyond the margins of said blade and leaving said blade substantially resilient, a handle connecting portion of approximately the same thickness as the combined thickness of said blade and said flanges integral with and projecting longitudinally beyond said flanges and said blade at one end of the latter, and a hollow handle integral with and projecting longitudinally beyond said connecting portion; a sheet of elastic material fitted within the area bordered by each of said flanges at the respective sides of said blade and its edge adjacent the inner side of the adjacent flange and also having its outer surface approximately in the same plane with the outer surface of said adjacent flange; and a substantially inelastic section of textile material having the same area as and attached to the concealed side of each of said sheets and also adhesively attached to said blade within the area bordered by one of said flanges and having its edge adjacent to the inner side of said complementary flange.
3. In a table tennis bat, a relatively thin resilient blade having numerous relatively large holes therethrough, marginal flanges integral with and projecting laterally beyond opposite sides of said blade, a section of inelastic textile material adhesively attached to each side of said blade within the area bordered by the complementary one of said flanges and having its edge adjacent to and contacting the inner side of said complementary flange, a sheet of imperforate elastic material attached to the outer side of each of said sections and cooperating with said sections to confine air within said holes and also having its edge adjacent to and contacting the inner side of said complementary flange and also having its outer surface approximately in the same plane as the outer side of said complementary flange, numerous projections integral with the outer side of each of said sheets projecting outwardly beyond the plane of said complementary flange, a handle connecting portion integral with and projecting longitudinally beyond one end of said blade and having a thickness approximately equal to the combined thickness of said blade and said flanges and leaving said blade resilient, and a handle integral with and projecting longitudinally beyond said connecting portion.

ELMER J. TIMMERMANN.
